UNITED STATES PATENT OFFICE.

ARNOLD STUCKI, OF ALLEGHENY, PENNSYLVANIA.

CAST TRUCK-BOLSTER.

No. 825,011.

Specification of Letters Patent.

Patented July 3, 1906.

Application filed October 25, 1905. Serial No. 284,394.

To all whom it may concern:

Be it known that I, ARNOLD STUCKI, a resident of Allegheny, in the county of Allegheny and State of Pennsylvania, have invented a new and useful Improvement in Cast Truck-Bolsters; and I do hereby declare the following to be a full, clear, and exact description thereof.

This invention relates to cast bolsters for railway-trucks and the like.

The object is to provide a cast-bolster which is strong vertically and horizontally, which is of the minimum weight, which has strong box end sections, with stiffener for the column-guides, and especially one which can be manufactured with ease and facility.

The invention consists of a bolster having the special features hereinafter described and claimed.

In the accompanying drawings, Figure 1 is a plan view of the bolster. Fig. 2 is a side view of the same. Fig. 3 is an end view of the same; and Figs. 4, 5, and 6 are cross-sections taken, respectively, on the lines 4, 5, 5, and 6, Fig. 2.

My improved bolster has a body which is substantially T shape in cross-section, having the vertical web 2, bottom flanges 3, and top flanges 4, the former preferably being narrower than the latter. At the middle of the bolster is the usual center-bearing 5, which is stiffened by means of the webs or fillets 6 uniting the flanges 3 and 4 and web 2.

The ends of the bolster are substantially box-shaped, having the top web 8, bottom web 9, and side webs 10. The latter have formed integrally therewith the column-guides 11. The central web 2 of the bolster continues through the box-shaped end, as shown in Fig. 1, and in said box-shaped end there is also provided a transverse vertical web 12, which extends between the column-guides and serves to keep the bolster square, brace the column-guides, and stiffen the spring-seat, so as to be able to take the thrust of the springs from underneath. The box is open at the end of the bolster.

In order to give the bolster great strength

against horizontal stresses, the edges of the top flanges 4 are thickened by being provided with beads or the like 14, as shown in Fig. 5. These beads are each of less thickness than the thickness of the flanges 4, this being done in order to facilitate the manufacture. These cast bolsters are made from patterns which are divided vertically through the web 2 of the bolster. The flanges 3 and 4 are slightly tapered, so as to facilitate the removal of the pattern from the mold. The beads 14 are provided for by strips separate from the main portion of the pattern, so that after the main portion of the pattern has been withdrawn these strips can be moved slightly inwardly and then withdrawn. This is made possible because they are of less thickness than the flange itself.

The bolster described is of minimum weight, has great tensile strength both horizontally and vertically, and has a strong box end section, which is stiffened by a transverse web in the line of thrusts of the column-guides and spring-seat. The horizontal strength of the bolster is very largely increased by the thickened edges of the top flanges. Inasmuch as the added metal is of less thickness than the flange itself, they can be formed by a strip separate from the pattern, thus greatly facilitating the manufacture and making it possible to mold the bolster without the use of large, troublesome, and expensive cores.

What I claim is—

1. A cast bolster having a web and flanges, said flanges having their edge portions reinforced or thickened by beads not thicker than the flanges themselves.

2. A cast bolster having a vertical web and top and bottom flanges, said top flanges having their edge portions reinforced or thickened by beads not thicker than the flanges themselves.

In testimony whereof I, the said ARNOLD STUCKI, have hereunto set my hand.

ARNOLD STUCKI.
